UNITED STATES PATENT OFFICE.

GEORGE W. GRACE, OF PITTSBURG, PENNSYLVANIA.

CURTAIN-POLE.

No. 796,840

Specification of Letters Patent.

Patented Aug. 8, 1905.

Application filed February 16, 1905: Serial No. 245,852.

To all whom it may concern:

Be it known that I, GEORGE W. GRACE, a citizen of the United States of America, residing at Pittsburg, in the county of Allegheny and State of Pennsylvania, have invented certain new and useful Improvements in Curtain-Poles, of which the following is a specification, reference being had therein to the accompanying drawings.

This invention relates to certain new and useful improvements in curtain-poles, and has for its object to provide a novel form of pole wherein the use of rings is dispensed with and novel means employed for securing one or more curtains to a pole.

Another object of this invention is to provide a curtain-pole which will be extremely simple in construction, strong and durable, comparatively inexpensive, and highly efficient for retaining one or more curtains in position in front of a doorway or window.

A further object of this invention is to provide novel means for securing one or more curtains to a curtain-pole, whereby the curtains will not be disfigured or injured by securing them to a pole, the fastening I have employed enhancing the general appearance and adding to the merits of the same.

With the above and other objects in view the invention finally consists in the novel construction, combination, and arrangement of parts, which will be hereinafter more fully described and then specifically pointed out in the claims, and, referring to the drawings accompanying this application, like numerals of reference designate corresponding parts throughout the several views, in which—

Figure 1 is a front elevation of my improved curtain-pole, illustrating two curtains as secured to my improved pole. Fig. 2 is a fragmentary elevation view of my improved pole. Fig. 3 is an end view of the same, and Fig. 4 is a vertical sectional view of a pole constructed in accordance with my invention.

In the accompanying drawings I have illustrated a pole 1, which may be made of any desired length and diameter, and this pole which I employ is somewhat similar to the ordinary type of curtain-poles at present used, with the exception that I provide said pole with a plurality of longitudinally-dis-

posed recesses 2. In these recesses I mount a piece of resilient material 3, such as rubber.

Upon the pole in front of each recess I secure an ornamental escutcheon-plate 4, the contour of which conforms to the periphery of the curtain-pole. Each plate is secured to the pole by a plurality of pins 5, or other suitable fastening means may be employed. Each plate is provided with a central aperture 6, and adapted to pass through said aperture and engage in said material is a tuberous pin 7.

By referring to Fig. 1 of the drawings it will be observed that I have employed a pin 7 for retaining the curtain upon the pole 1, and these pins are adapted to be inserted through the top edge of the curtains to retain the same in engagement with the curtain-pole. I preferably provide the ends of my improved curtain-pole with ornamentations 8 8, which may be of any desired design.

From the foregoing description, taken in connection with the drawings, it will be observed that I have provided a curtain-pole which is extremely simple in construction and to which can be readily attached one or more curtains, it being obvious that the poles can be made of any desired length and a plurality of pins employed for sustaining curtains upon my improved pole.

It will be noted that various changes may be made in the details of construction without departing from the general spirit and scope of the invention.

What I claim, and desire to secure by Letters Patent, is—

1. A device of the class described, comprising a pole having a plurality of recesses formed therein, resilient pieces of material mounted in said recesses, escutcheon-plates mounted upon said pole in front of said recesses, pins passing through said plates and adapted to engage in said material, substantially as described.

2. A device of the class described, comprising a pole, resilient material carried by said pole, plates mounted upon said pole and covering said material, pins adapted to pass through said plates and engage in said material, substantially as described.

3. In a device of the character described

the combination of a round pole having a plurality of alined recesses on one side, pieces of resilient material arranged in said recesses, curved plates attached to the pole and covering said resilient material, said plates being formed with central openings and said pieces of material being formed with coinciding recesses, and pins adapted to pass

through the openings of the plates and into the recesses in the resilient material.

In testimony whereof I affix my signature in the presence of two witnesses.

GEORGE W. GRACE.
